KNITTING MACHINE

Philip Kaplan, Lowell, Mass.

Application December 18, 1933, Serial No. 702,943

4 Claims. (Cl. 66—24)

This invention relates to knitting machines of the type in which there is what is known as a dial with dial needles which operate in a radial direction from the center and what is known as a cylinder which has cylinder needles which in a vertical plane operate at right angles to the dial needles, the cylinder needles being arranged at equal distance around a central axis which passes through the center of the circle on which the dial needles are located and at right angles thereto.

The main purpose of the device is to provide mechanism by which what is known as a rib stitch can be shifted to a shaker stitch thus avoiding the necessity of forming the rib on one machine and the shaker on another and then sewing them together.

My preferred construction is on the type of knitting machine in which the cylinder needles are on the inside and the dial needles on the outside, but the same devices can be used on machines in which the cylinder needles are on the outside and the dial needles are on the inside.

I am aware that transfer needles or transfer members in which there are prongs which slide up and down in grooves on each side of a latch needle have been used for transferring stitches, but on account of their construction they do not positively pick up the loop and they do catch the fiber thus causing flaws.

The main feature of my device is the use of a transfer needle which is located parallel with and slidably along that part of a latch needle which is on the opposite side from the latch. Ordinarily, this would be in a position between the dial and the cylinder needles. This transfer needle is split at its pointed end and is provided with an eye and holding notches so arranged that a latch needle can go through the eye below the notches before the transfer needle is withdrawn.

While the latch needle is advanced or while it is being retracted, the transfer needle pushes up behind it and its split point, which moves along the back of the latch needle, easily passes through between the sides of the loop of yarn caught by the latch needle, there being an open space at the back of the latch needle on account of the nature of the formation of the loop.

At the sides, the yarn is pulled in close to the latch needle, but at the back, there is obviously an open space and it is through this open space that the point of the transfer needle passes.

The movements of the parallel latch and

transfer needles are so timed that the notches across the eye of each transfer needle will receive the loop as it slips over the end of the latch needle and thereby hold it so that there is ample space through the eye below the notches for a latch needle, moving at right angles, to pass through the loop.

In the drawings, Fig. 1 is an elevation view of a complete knitting machine of my preferred type.

Fig. 2 shows the shaker stitch and rib stitch at their junction point.

Fig. 3 is an elevation showing a garment started with a half cardigan stitch which merges into a rib stitch and then is transferred by my machine to a shaker stitch.

Fig. 4 is a section on line 4—4 of Fig. 2 and Fig. 5 is a section on line 5—5 of Fig. 2.

Fig. 6 is a plan view of the top of a knitting machine showing some parts broken away to show the construction.

Fig. 7 is a plan view of the top of a knitting machine with controlling parts removed showing diagrammatically the positions of the various cams or switches and needles.

Fig. 8 is a horizontal sectional view showing a detail of the arrangement of the cam grooves in connection with the dial needles.

Fig. 9 is a vertical section through the cylinder and dial some parts being omitted for clearness.

Fig. 10 is a developed view of a cylinder section of the cam cylinder, the section being cut through so as to show the cam grooves of the cylinder cam.

Fig. 11 is a diagrammatic sectional view showing the relation between a transfer needle and its adjoining latch needle which, as shown, is one of the cylinder needles, and the relation of both to the cam grooves. This, however, might be a vertical section through a dial equipped with transfer needles instead of a cylinder equipped with transfer needles.

Fig. 12 is an inside view of a transfer needle.

Figs. 13 and 14 are enlarged detail views from the top showing how a loop of yarn is taken from a cylinder needle by a transfer needle and then by a dial needle from the transfer needle.

Fig. 15 is an enlarged side view showing the position of the yarn, the transfer and latch needle when the latch needle is about to let go of the loop and leave it on the transfer needle.

Figs. 16 and 16A are enlarged views showing how, as the transfer needle is retracted, the latch needle, which is at right angles to it, spreads the

eye of the transfer needle and takes off the loop of yarn.

Fig. 17 is an enlarged horizontal section of a cylinder with transfer needles and latch needles.

5 Fig. 18 is an enlarged detail view showing the action of the compound cams on the dial needles.

Fig. 19 is a section on line 19—19 of Fig. 19A and Fig. 19A is a horizontal cross section through the cam carrier plate and its grooves showing 10 another type of cam or switch from the top.

Figs. 20, 21, 22, 23, 24 are vertical section detail views showing the action of the latch needles and the transfer needle.

Fig. 25 is a plan view showing the mechanism 15 for operating the compound cam shown in different positions.

Figs. 26 and 27 are elevations showing the compound cam and its operating mechanism from different positions.

20 Fig. 28 is a view of the disc or plate which covers or uncovers the notches in the compound cam.

Fig. 29 is a horizontal section on the line 29—29 of Fig. 30.

25 Fig. 30 is a view of the compound cam and its operating mechanism from the opposite side from Fig. 27.

Fig. 31 is a diagrammatic elevation showing 30 how the rolling disc of the compound cam rolls over the cam followers of alternate needles.

Fig. 31A is a horizontal sectional view looking down on the line 31A—31A of Fig. 28. It is associated with a diagram showing as well as possible the direction of the various rolling and sliding 35 movements which the compound cam produces on the needles.

Fig. 32 is a vertical section through one edge of one of the dial needle grooves to show the relation of the parts to the compound cam.

40 In Figs. 1, 6, 7, 8, 9 and 10 is represented a type of machine in which the dial D is on the outside and the cylinder C is on the inside.

As it is customary to permit the knitting material to go between the dial and the cylinder, the 45 cylinder is supported by means of a central shaft S carried by suitable supports shown as bars 2 and 3 extending across from the cam carrier plate A which is supported on frame F of the machine.

Plate A usually has gear teeth 101 which mesh 50 with a small driving gear 102 and rest on other gears such as 402, 502. Plate A also has a projecting annular flange 113 which is held in place and guided by slotted heads 104, 104 as it revolves.

55 In the bottom of plate A is the usual dial needle guide groove 105 having the usual retracting cam part 106 and an advancing cam slot 107, through which I project my special compound cam K, which engages the butts or cam followers 7 of 60 some or all the dial needles H and directs some or all of them into the advancing cam slot 107 along which they travel until they reach the part 106 which retracts them and directs them to the main annular groove 105 where they may rejoin any others which have continued along by-pass 108.

Cam carrier plate A, as is common in such machines, carries the various trip devices and cams well known to the trade. Teeth 101 and gear 102 are all driven by the drive shaft S, S of any usual type.

G represents a cylinder needle of the usual latch type and H represents a dial needle of the usual latch dial type while T represents a transfer needle.

Y, Y represents the knitting yarn or thread.

In every latch needle, 5 represents the hook, 6 the latch and 7 or 40 the needle butts or cam followers all of well known type.

5 Dial needles H slide in horizontal grooves or slots 103 in dial D, cylinder needles G slide in vertical slots 203 near the inside of cylinder C and transfer needles T slide in vertical slots 303 also in cylinder C, but nearer its outside each being close to and behind a slot 203 and a cylinder 10 needle G. Each cylinder needle G has a butt 40 which projects inward through a short vertical slot 240 through the inside of cylinder C and into a cam groove indicated generally by 205 in the outside of cam cylinder L and above a butt 33 of 15 an adjoining transfer needle T which butt 33 also projects inward through a short vertical slot 233 in cylinder C, which is under and in line with the slot 240, and into a cam groove indicated generally by 305 in the outside of cam cylinder L. 20 Needles G and T can, therefore, be operated independently of each other.

Each transfer needle T has a comparatively straight shank 30 which slides in its groove 303 and has a butt 33 while its pointed end 31 is bent 25 in towards an adjoining cylinder needle G so that, preferably, it will scrape along the back of that needle as it moves up. Needle T has an eye 34 and the notches 35, 35 midway up are on the side next the needle G, the eye 34 being so formed at 30 the top that its sides converge to the split 36 which extends up to the point. There should be enough space in eye 34 below the notches 35, 35 and above the top of the cylinder C for a dial needle H to pass through and the dial needles 35 should be so positioned that, when they are successively moved forward horizontally, they will pass through the eye of a transfer needle if there is such a transfer needle opposite to the one advanced.

40 Shaft S, at its bottom, carries a plate 200 and the usual revoluble cam cylinder L, in the outside of which is the usual cylinder needle guide groove 205 having the usual retracting cam part 206 and a cylinder needle advancing cam slot 45 207 through which I project my retractable cylinder needle cam M which advances all or some of the cylinder needles G while 206 retracts them and 205 keeps them retracted.

208 is one by-pass for the cylinder needles 50 through which the butts or cam followers of needles which are temporarily or permanently out of action will travel.

Cylinder C rests on plate 200 and is kept from 55 revolving by dogs such as 60 which extend outward and rest against wheels such as 161 on arms such as 162 fixed to dial D in a well known manner.

Shaft S, cam cylinder L and needle cylinder C 60 are all somewhat longer than usual to permit the installation of transfer needle cams or other suitable operating devices below those of the cylinder needles.

I prefer to provide, at a point in advance of 65 cam M, an additional set of grooves extending up from groove 205, one 407 being a slot for advancing and the other 406 for retracting the cylinder needles at the right time. Through cam slot 407, I can project my supplementary cylinder 70 cam or switch O and can retract it at the right times.

The part 408 of groove 205 serves as a by-pass between 406 and 407, but is normally a part of 75 groove 205 through which the butts 40 of the

cylinder needles travel except when the transfer is going on.

Below and between the regular and supplementary cylinder needle cam grooves, I provide a transfer needle guide groove 305 having a retracting part 306 similar to 206 and a transfer needle advancing cam slot 307 through which I project my retractable transfer needle cam N which when in operation projecting through slot 307 will advance the transfer needles T, T while 306 retracts them and 305 keeps them retracted. 308 is the by-pass forming part of groove 305 through which the transfer needle butts 33 travel except when the transfer is going on.

15 When both cylinder needles and transfer needles are out of action while the dial needles are forming the shaker stitch, all the cylinder needle butts such as 40 remain in this annular groove 205, 208, 408 and all the transfer needle butts 33 remain in annular groove 305, 308.

The cam slots such as 107, 207, 307 and 407 extend entirely through either the dial cam plate or cam cylinder and with the respective cams or switches which pass through them form part of 25 the cam groove for the butts of the dial needles, the cylinder needles or the transfer needles respectively.

While I show the cams or switches such as K, M, N, O in the form of revoluble discs, they are 30 shown in this manner to indicate that such a construction can be used and that a compound cam such as K, which really means two cams both of disc form, could be substituted for the cams M, N or O if it was so desired and could 35 be operated by mechanism such as that shown in the drawings Figs. 25 to 32.

A simpler form of switch is shown in Fig. 19 at V. This is merely a flat piece of metal which can be moved into or out of any one of the grooves 40 such as 105, 205, 305, 405, to switch the metal butts away from the by-pass such as 108, 208, 308 or 408, thus advancing the respective needles, or can be retracted allowing them to go through the by-pass.

45 Moreover, in the type of knitting frame where the dial is on the inside and the cylinder on the outside, these respective cams or switches can be suitably located, the only thing necessary being that some sort of selective cam must be used 50 to bring all of the needles of the dial or all of the needles of the cylinder into action at the time the shaker stitch is to be made, and to take out of action those opposite any needles of the other set when the rib stitch is to be made.

55 The cam or device K might be replaced by any device which would allow the cam followers of certain needles to pass, while switching the others into an advancing slot or groove, associated with another cam or switch which would either advance all of them or switch all of them into an advancing groove. For suitably moving the various cams or switches, I find it convenient to use the well known chain timing device.

60 The chain timing devices Y include a gear 502 connected by a gear chain with a sprocket 20, chain 25 and the various high links or fingers 22, 23, 24 and 21 which, at suitable intervals, are brought up proximate a member 4 which raises or allows to drop the control dog J which carries 65 control members such as 12, 13, 14, 11 of different lengths and positions. By the raising and lowering of dog J, these control members are moved more or less up and down outside of plate A so that they will be struck by the operating arms of the various cam mechanisms for operat-

ing the various needles and other parts which are carried by plate A and extend outward or upward therefrom.

K represents a preferred type of compound rotary cam which, as shown, I use for operating the 5 dial needles. This comprises a support 50 fixed to the revolving cam carrier plate A which supports a freely revoluble disc 51 having diagonal notches 52 in its periphery so spaced that each notch will permit the passage or rather will not 10 strike the butt 7 of alternate dial needles H. Disc 51 is set at such an angle that it acts as a plough as it sweeps around with plate A successively engaging the butts 7 or alternate butts 15 as the case might be, as it revolves by friction.

As disc 51 is positioned and rolls in the direction of the arrow W, in Fig. 31A and slides also in the direction of arrow Z, when plate 54 herein-after described or the part 152 between notches 52 engages a butt 7, its needle H, being slidable 20 in its groove 103, is pushed from X to Y, but as each notch 52 rolls down and then up, as shown in Fig. 31, it allows a butt 7 to pass therethrough and the corresponding needle remains in its place. 25

As shown, the notches 52 are so spaced and the periphery of revoluble disc 51 is of such length that as it is revolved by frictional contact with the surface of dial D, the notches 52 will register with the butt 7 of each alternate dial needle H. 30 As shown in Figs. 31 and 32, the disc 51 not only revolves thus causing the teeth 152 between the notches 52 to lift, but the whole movement is compound, the result being that while a butt 7 which registers with a notch 52 will not be moved, 35 the alternate butts 7 will engage the teeth formed at 152 between the notches and the movement of these teeth as the disc 51 revolves will be to switch those particular needles into the advancing slot 107, as shown in Figs. 18 and 31. The teeth 40 152 thus engaging the butts 7 correct any tendency of the disc 51 to slip so that the parts will not register and the action between them not only advances the alternate butts, but keeps 45 the disc 51 revolving and slipping correctly. This action moves these cam butts 7 of alternate needles towards the center at the desired time.

50 54 is a plate or plough which is slidable up and down behind disc 51 so connected with retracting and advancing devices, shown as trip mechanism W, W that it can be moved up from behind the notches 52 or moved down to close them at the back. When plate 54 comes down behind the notches, instead of each alternate dial needle being moved, all the dial needles are successively 55 moved forward.

The trip mechanism W, W shown in Figs. 25 to 30 includes a spring 150 which tends to move plate 54 down behind the notches 52. This spring 150 is shown as wound around a shaft 151 which carries plate 54 and the notched ratchet wheel 157 which is turned from time to time by a pawl 153 having a spring 154 and carried by an arm 155 on the top of a shaft 156 from which extends an arm 58 such arm being in a position where it extends outward and can be struck by members 12, 12 carried by dog J when dog J is raised to a certain predetermined height by a suitable link of the timing chain.

Shaft 151 also carries a trip and cam 159 which 70 engages a trip cam member 158 fixed to support 50 on dial D. These parts are so adjusted that when each member 12 is struck by arm 58, it partly turns shaft 156 which swings arm 155 with pawl 153 enough to turn ratchet 157 and member 159 75

one-quarter turn, so that it rides on 158 thus lifting shaft 151 and plate 54 from notches 52. When the second member 12 is struck, another quarter turn is made and plate 54 is lifted and held away from notches 52 while the rib stitch is being made. Members 12, 12 are dropped out of the way until the transfer when they are moved up and member 159 drops into 158 allowing plate 54 to block the notches 52 so that all the dial needles H will then be advanced as cam K sweeps around with plate A.

Plate 54 is carried by and guided by bracket plate 254 which slides on guides 255 forming part of support 50 and shaft 151 carries it up and down and its lower end revolves in bracket plate 254.

To bring the cams M, N and O into operation and to take them out of operation, I utilize a type of spring actuated latches 81, 83 and 84 of a well known type which are caused to move at the proper time by members such as 11, 13, 14. Each of these latches is on a pivot and spring pressed so that one part normally projects outside plate A and is pushed out by a spring, but when it is struck or when it strikes one of the control members, it is moved and is caught and held by a trigger until the trigger is released by striking a suitable member, when the latch springs back to its usual position. These latches are old and well known on knitting machines. Latch 81 is connected by an arm 71 with cam M, latch 83 by arm 73 with cam O and latch 84 by arm 74 with cam N.

Each one of the control arms 71, 73, 74 is bent over and down inside of the cylinder C and carries respectively one of the cams M, O or N and is attached to its latch in such a way that as the latch is moved, its control arm slides longitudinally carrying with it, its appropriate cam either into action through its appropriate slot or out of action.

The particular arrangement of the control members 11, 12, 12, 13 and 14, of the latches 81, 83, 84 and device W is a matter of adjustment, but in the simple form of the machine set for transferring rib to shaker stitch and in the preferred form, the arrangement is as follows:

The machine may be started with any stitch such as that known as half cardigan and is then shifted to rib in which all of the cylinder needles and those of the dial needles which are not opposite them are doing the work.

At the desired time, the regular cylinder cam M is withdrawn and at the same time the extra cylinder cam O, which is ahead of it, is pushed through its slot and at the same place the transfer cylinder cam N is pushed through its slot, the result being that there is no more rib stitching, but on that particular round all the rib stitches are taken off and as the regular cam M is out of action and, as the disc 54 on dial cam K is brought into action at such time as to advance the dormant or alternate dial needles through the transfer needles, the transfer is complete.

For transferring with my device, it is necessary that certain needles on the dial and certain needles on the cylinder should be opposite to each other so that between them can be located a transfer needle through the eye of which either one or the other can be pushed at the proper time, and it is necessary to have a special, selective or compound cam or other device of such character that it will operate part or all of the needles, such as those on the dial, according to whether shaker or rib stitch is to be made.

As in knitting a rib stitch, the dial needles are timed to advance ahead of the cylinder needles, I find it convenient to use an additional cam action positioned ahead of the regular cylinder cam action with the transfer cam action between them. This makes five cam actions namely: one for all the dial needles, one for part of the dial needles, the regular cylinder needle action, the special cylinder needle action and the transfer needle action. This means that there may be five advancing and five retracting movements for the needles and it also means that there are preferably five cams or switches which are brought into and out of action in timed relation one to the other.

To anyone familiar with the art, it is obvious that I can use my transfer needles and cams with suitable timing devices for making various fancy stitches and modifications and that if the shaker stitch is made on the cylinder needles, I can use my transfer needles on the dial and in fact I can use transfer needles associated with some of the needles of the dial and also of the cylinder or in fact with all of these needles, if there was any object in so doing, cutting my cams and arranging my timing devices in such way that any of the needles can be caused to function according to the stitch desired.

If transfer needles are associated with the dial needles, there should be a compound cam to operate the cylinder needles. I may use transfer needles associated with both the cylinder and the dial and in such case, I use a compound cam with both cylinder and dial.

I claim:

1. The combination in a knitting machine having a dial with radial latch needles and a cylinder with axial latch needles, such cylinder needles being positioned in the same vertical plane with some of the dial needles; a series of transfer needles each parallel with and positioned between a cylinder needle and a dial needle, the point of each transfer needle being slidable along a cylinder needle, and being longitudinally split from its pointed tip to an eye the opposite top walls of which converge, and having a holding notch on the side next the cylinder needle near the top of the eye; operating means including a retractable cam adapted to move the cylinder needles successively up and down and to cause them to remain out of action; operating means including a retractable cam for successively moving the transfer needles up and down and to cause them to remain out of action; operating means for successively moving the dial needles in and out including a compound cam for advancing all or part of the dial needles, said cam comprising a revolute disc member which is peripherally notched in such manner as to operate the dial needles which are not opposite the cylinder needles, and a retractable plough to cover or uncover some of said notches so that together they will advance all of the dial needles; and timing means for causing the respective operating means to operate the cylinder needles with dial needles which are not opposite and to put them out of operation, to bring the transfer needles into operation to receive the loops from the cylinder needles as the cylinder needles go out of operation, to cause the hooks of some dial needles to pass through the eyes of transfer needles, and to withdraw the transfer needles from operation.

2. The combination in a circular knitting machine having needle carriers; of a compound cam comprising a revolute disc having notches in its

edge and a slidable plough having a plain edge, and means to cause said plough to move so that some of the notches are covered or uncovered by the plough at predetermined intervals.

- 5 3. The combination in a circular knitting machine of two sets of longitudinally slidable latch needles some of which are positioned in the same plane at substantially right angles with each other and with their hooks in proximity; of a set 10 of transfer needles positioned between some of the latch needles which are at substantially right angles with each other and in the same plane, each transfer needle being pointed at its end which is nearest the hook of the adjoining latch 15 needle said point being split to form an eye the upper inside edges of which slope towards each other, said point being in contact with and slidable along the edge of such latch needle which is opposite the hook and said eye being of a width to permit the passage of one of the other latch needles which is at right angles thereto and in the same plane; together with means for reciprocating both sets of latch needles and of transfer

needles and of throwing some or all of each set into or out of action.

4. The combination in a circular knitting machine of two longitudinally slidable latch needles positioned in the same plane at substantially 5 right angles with each other and with their hooks in proximity; of a transfer needle slidable along and behind one of the latch needles between it and the other latch needle, said transfer needle being pointed at one end which is nearest the 10 hook of its adjoining latch needle, said pointed end engaging and being slidable along the edge of such latch needle which is opposite its hook, having a loop holding stop and being split to form an eye the upper inside edges of which slope 15 towards each other said eye being of a size to permit the passage of the other latch needle which is at right angles to the transfer needle; together with means for reciprocating the latch 20 needles and the transfer needle and of throwing some or all of each set into or out of action.

PHILIP KAPLAN.
